UNITED STATES PATENT OFFICE

ERA E. STUMP, OF EAST CLEVELAND, AND THEODORE A. KNOEDLER, OF SHAKER HEIGHTS, OHIO

DRIVING FAUCET

Application filed November 30, 1929. Serial No. 410,855.

The objects of the invention are to provide a simple and efficient form of a driven and self puncturing and pouring tube or faucet for a sheet metal container, and which is so constructed that the faucet tube when driven will cut its own way through the side or top of the can, and will provide an opening through which the liquid will enter the faucet.

10 The invention also provides means for leaving an unsevered neck or connecting part between the cut out portion and the wall of the can which will prevent that portion from falling into the can.

15 The invention also provides means for anchoring the faucet tube securely in the opening which it has made, and means for sealing the opening so that the container will remain air tight after it has been punctured.

20 The faucet tube is preferably constructed from a sheet metal blank or stamping; and locking bosses, and screw threads for the adjustment of a clamping or wing nut and terminal eyes for the attachment of a pivoted valve or closure, may be simultaneously formed upon the metal blank.

To accomplish these and other useful results the invention comprises, the method of construction and the combination and arrangement of parts, hereinafter described, illustrated in the accompanying drawings and particularly pointed out in the claims.

30 In these views Fig. 1 is a vertical section of the device; Fig. 1a is a modified form showing a washer set in a recess; Fig. 2 is a front elevation thereof; Fig. 3 is a perspective of the pouring tube; Fig. 4 is a perspective of the clamping nut; Fig. 5 is a plan of the blank stamping from which the tube is rolled; Fig. 6 is an edge view thereof and Fig. 7 is a transverse section of the lower portion of the faucet.

35 In these views A is the tube, which is first stamped from a sheet of metal in the flat form shown in Fig. 5 and is then shaped into a tube as shown in Fig. 3 with the longitudinal edges closely meeting at B. These edges may then be cemented or soldered tight. Wedge shaped pointed cutting projections C, C, diametrically opposed to each other are formed

upon the inner edge of the blank and after the blank has been shaped into the form of a tube, the edges of the projections are bevelled by grinding at D to sharpen them for cutting through the wall of the can.

40 The inner cutting edges of the projections are left prominent and the opening will be narrower in one direction than in the other. Also some of the recesses between the projections are more deeply cut at E, than the other at F, thus preventing the piece G cut from the can from being completely severed therefrom, and leaving a short retaining neck therefor at H.

45 This construction also causes the edges of the opening in the can to roll inwardly as the cutting edges pierce through them, thus forming them in such a manner that when engaged with the bosses I, the bosses will always tend to close the opening as shown in Fig. 2.

50 Intermediate of the cutting points C and positioned at a higher level are shown the diametrically opposed bosses, I, I, which are punched in the blank, at the time of stamping.

55 These bosses when the tube is revolved, will lock underneath the wall W of the can and a wing nut J is employed between which and the bosses I the metal wall of the container is clamped.

60 Diagonal ridges or threads K, K, are stamped or rolled upon the flat metal blank, which, when the blank is shaped into a tube, produce screw threads, over which the wing nut J is adjusted.

65 A washer L is employed underneath the nut, to make the upper surface of the joint between the tube and wall air tight.

70 At the upper edge of the blank are formed the ears M, M, upon which hinge ears N, N, of the finger operated valve, O, are pivoted. P is the pivot pin therefor and Q is a compression spring which retains the valve in position when released from the finger.

75 A washer R may be set in a recess S in the upper end of the tube as shown in Fig. 1a, or a rubber disc R' may be set in the valve O as shown in Fig. 1.

80 The device is easily placed, first, by driving the tube through the wall of the container and then by revolving the same until the bosses I

engage underneath the wall of the container.

The wing nut is then revolved until the tube is firmly secured in place.

Having described the invention what we 5 claim as new and desire to secure by Letters Patent is:

1. A blank for a sheet metal driving tube, said blank having spaced points at its lower edge separated by deep recesses, one recess 10 being cut deeper than the other and provided with bosses impressed therein and spaced therefrom, and also provided with a transverse portion composed of screw threads impressed thereon.
- 15 2. In a driven faucet, a tubular body, having diametrically opposite angular extremities forming piercing points, the sides of said points being bevelled to form cutting edges, and adapted to turn down the opposite edges 20 of the opening produced thereby, said tubular body being provided with diametrically opposed bosses which when said body is revolved will engage underneath said turned down edges and means adjustable on said 25 body for clamping said bosses upon said turned down edges, the recess upon one side of said tube between said piercing points being deeper than the recess upon the other side to provide an unsevered neck to prevent the 30 total detachment of the piece partially severed from the wall of the can.
- 35 3. A driven faucet tube comprising, a rolled sheet metal stamping having its longitudinal meeting edges welded together, and having screw threads raised thereupon intermediate of its ends, a clamping nut therefor, the inner end of said tube being bevelled to provide opposite cutting points with sharp edges, the recess in one side of said tube 40 being deeper than the other to prevent the complete release of the portion cut away thereby, and opposite bosses on the sides of said tube intermediate of said bevelled and threaded portions and a clamping nut on 45 said threaded portion.

In testimony whereof we affix our signatures.

IRA E. STUMP.
THEODORE A. KNOEDLER.
